UNITED STATES PATENT OFFICE

110,145

DESIGN FOR A COMBINED CANDLESTICK AND FLOWER HOLDER

Gretchen Goughnour, York, Pa., assignor to Lewis P. Weil, Philadelphia, Pa.

Application March 8, 1938, Serial No. 75,658

Term of patent 3½ years

To all whom it may concern:

Be it known that I, Gretchen Goughnour, a citizen of the United States residing in York, in the county of York, State of Pennsylvania, have invented a new, original, and ornamental Design for a Combined Candlestick and Flower Holder, of which the following is a specification, reference being had to the accompanying drawing, forming part thereof.

Fig. 1 is an elevation of a combined candlestick and flower holder, showing my new design.

Fig. 2 is a plan view of same.

Fig. 3 is a vertical section of same.

Figs. 2 and 3 show the candle holding formation secured entirely within the surrounding flower receiving formation.

I claim:—

The ornamental design for a combined candlestick and flower holder, as shown and described.

GRETCHEN GOUGHNOUR.
